UNITED STATES PATENT OFFICE

2,156,373

APPAREL BELT

John R. Craighead, Denver, Colo.

Application May 9, 1938, Serial No. 206,824

3 Claims. (Cl. 241—8)

This invention relates to improvements in apparel belts.

An object of the invention is to provide, in a belt of this character, an inner pocket of a novel type that is not detectable from the outside, for the reception of valuable articles.

Another object is the provision of a container or envelope of novel construction, that is adapted to be readily inserted and withdrawn from the pocket.

Other objects and advantages reside in details of design and construction which will be more fully disclosed in the following description and in the drawing wherein like parts have been similarly designated and in which:

Figure 1 is a fragmentary inner surface view of a belt made according to this invention;

Figure 2 is a similar view showing parts of the belt in another position;

Figure 3 is a detail view of a container envelope for the improved belt;

Figure 4 is a cross sectional view along line 4—4 of Figure 2, and drawn on a larger scale; and

Figure 5 is a detail view of an article folded to be placed in the pocket of the belt.

In the drawing reference character 10 denotes a belt for personal wear, preferably made of leather, fabric or the like, having an end portion 10a that is folded through and around an ordinary belt-buckle 12 and that is secured thereto by rivets 13. The end 10a laps back on the belt 10.

In the end portion 10a, is a fastening, such as a friction snap-button 14 that normally holds the end of the belt tightly closed over a pocket 15 that is formed by sewing a piece of leather, cloth or the like onto the inner surface of the belt 10, along lines 16. A cooperative part 14a of the snap-button is on pocket 15. The end 15a of the pocket, that is adjacent the buckle and normally under the end 10a, is open while the opposite end is sewed closed as shown.

A container for articles to be carried in the pocket is provided, such as a flexible transparent envelope 17 that is sewed across each end at 17a and which has a tab 18 sewed thereon. The tab may be made of flexible material such as leather, cloth or the like. The envelope is adapted to slide into the open end 15a of the pocket 15, with the tab 18 projecting therefrom, and to be closed therein by the end 10a of the belt held by the snap-button 14. This arrangement is clearly shown in Figures 1 and 2. Obviously, the envelope 17 may be made of any suitable material other than that illustrated. It is preferably made of one sheet of material folded and closed at its ends and of a length

to slide into the pocket to the closed end thereof with the tab 18 projecting from the pocket. The material illustrated presents a smooth surface that facilitates easy sliding of the envelope 5 in or out of the pocket.

The end 10a of the belt with its snap-button 14, or other type of fastening, securely holds the envelope and contents within the pocket, and when the contents are to be removed, the belt-end 10a may be unfastened and bent up as shown in Figure 2, whereupon the flexible tab 18 is accessible to withdraw the envelope 17 with its contents, from the pocket. Paper money or other valuable articles may be folded as shown 15 in Figure 5, for placement in the envelope 17. If the envelope is made of transparent material, as illustrated, the contents thereof are readily seen and selected for removal by the owner when wanted.

When valuable articles are in the belt-pocket and the belt is being worn, they are safe from loss or unauthorized tampering and from theft. The arrangement disclosed provides most convenient accessibility to the pocket and its contents, by the owner. The pocket does not show 20 25 from the outside face of the belt and is not conspicuous even from the inner side.

The provision of the closing end 10a for the pocket, as an integral part and continuation of the belt 10, is an advantageous economic factor 30 in the production of a belt according to this invention, and the pocket positioned lengthwise of the belt may be made long enough to receive valuable papers or other relatively long and narrow articles. The carrying envelope 17 adds to 35 the convenience and safety of the combination.

What I claim and desire to secure by Letters Patent is:

1. In an apparel belt, a longitudinal pocket along an inner surface of the belt, having a 40 slot-like opening transverse to its length, an envelope slidable through said opening, and a flap composed of an end of the belt, folded inwardly and normally overlapping said opening.

2. An apparel belt having a longitudinal pocket open at one end, at the inner surface of the belt, an end-portion of the belt adjacent said pocket open end, being folded back thereover forming a closure for the pocket.

3. An apparel belt having a longitudinal pocket open at one end, at the inner surface of the belt, an end-portion of the belt adjacent said pocket open end, being folded back thereover forming a closure for the pocket, and a fastening 50 55 positioned to selectively hold said end portion over the pocket opening.

JOHN R. CRAIGHEAD.
